Filed Feb. 28, 1968, Ser. No. 10,762

Term of patent 14 years

Int. Cl. D21—03

U.S. Cl. D34—5

FIG. 1 is a rear side elevational view of a golf putter head showing my new design;

FIG. 2 is a front side elevational view thereof;

FIG. 3 is a front elevational view thereof;

FIG. 4 is a top plan view thereof; and

FIG. 5 is a bottom plan view thereof.

The shaft portion shown in broken lines in FIGS. 1, 3 and 4 is for illustrative purposes only.

The dominant features of my design reside in the full-line portions of the drawing and as characterized by the combination of the monograms and the particular golf club head shown.

I claim:

The ornamental design for a golf putter head, substantially as shown and described.
